UNITED STATES PATENT OFFICE.

HEINRICH PFLÜGER, OF FRANKFORT-ON-THE-MAIN, GERMANY.

DISINFECTANT VESSEL.

SPECIFICATION forming part of Letters Patent No. 744,978, dated November 24, 1903.

Application filed March 23, 1903. Serial No. 149,172. (No model.)

To all whom it may concern:

Be it known that I, HEINRICH PFLÜGER, a subject of the King of Prussia, Emperor of Germany, residing at Frankfort-on-the-Main, 5 Germany, have invented certain new and useful Improvements in Disinfectant Vessels, of which the following is a specification.

The subject of the present invention is a closure for disinfectant vessels. The disinfectant-gases are evolved within the vessel and are simultaneously forced outward on all sides and upward as well. This is effected by arranging, first, several horizontal equally-distaned nozzles, and, secondly, an upwardly-directed nozzle in a center tube of the closure. This latter nozzle in consequence of its special construction acts also as a safety-valve for the vessel.

In the accompanying drawings, in which 20 my invention is illustrated, Figure 1 is a vertical section of the closure. Fig. 1^a is a vertical section of the closure with the tube *e* rotatably mounted; Fig. 2, a plan view thereof. Fig. 2^a is a plan view of the closure shown 25 in Fig. 1^a; Fig. 3, a detailed view of the vertical nozzle, and Fig. 4 a modified form of horizontal nozzle.

a is a portion of the air-tight disinfectant vessel, within which the disinfectant-gases are 30 evolved by means of a fire kindled thereunder or by similar means. An opening *c* allows of the filling of the vessel with the disinfecting material. To the flange *b*, surrounding this opening, is screwed the socket-piece *d*, which is tapped to receive the threaded end of the vertical distributing-tube *e*. Into the sides of the latter are screwed several nozzles *f*, four being shown in the drawings. In the top of the tube *e* is also arranged 35 a vertical nozzle *g*, which in consequence of its special arrangement serves as a safety-valve. Into the tube *e* is screwed a sleeve *h*, having at its lower end a flange *k* and being closed above with a cap *i*. In the sides of 40 this sleeve are several openings *l*. Within this sleeve slides the vertical nozzle *g*, Fig. 3, having at its lower end a flange *n* and a collar *m*, between which are arranged the open-

ings *o*. A spring, bearing against the cap *i* of the sleeve and the collar *m* of the nozzle, 50 tends to keep the nozzle *g* in the position indicated in Fig. 1.

The gases on being evolved enter the distributing-tube *e* and pass out in the directions indicated by the arrows in Fig. 1. 55 Should the pressure within the vessel reach a dangerous height, the safety-valve comes into action. The nozzle *g* slides upward within the sleeve *h* under the excessive pressure within the vessel, overcoming the spring *p*, 60 until the openings *o* correspond with the openings *l*. The gases then find openings of considerably greater dimensions. One can also screw into the distributing-tube *e* bent horizontal nozzles, as shown in Fig. 4. The tube 65 *e* is not in this case rigidly secured, but is held in the socket *d* by means of suitable bearings, so as to be able to rotate. If now the gases stream out through these bent nozzles at a certain speed, the whole delivery apparatus is set into rotary motion, where an even greater diffusion of the gases is obtained. 70

What I claim, and desire to secure by Letters Patent of the United States, is—

1. In a closure for disinfectant vessels, a 75 delivery-nozzle sliding in a sleeve under the influence of a spring and having also lateral openings normally closed by said sleeve, said sleeve having openings, which under raising of the nozzle under excessive pressure coincide with the lateral openings in the nozzle, substantially as described.

2. In a closure for disinfectant vessels, a nozzle having an opening for delivery, a flange *n* and collar *m*, openings *o* between said flange 85 and collar, in combination with a spring *p* bearing against said collar *m*, and a sleeve *h* inclosing said spring and normally closing openings *o*, holes *l* being provided in said sleeve to coincide with openings *o* in case of 90 the nozzle rising under excessive pressure, substantially as described.

3. In a closure for disinfectant vessels, a delivery-nozzle sliding in a sleeve under influence of a spring and having also lateral 95 openings, openings in said sleeve, a tube into

which said sleeve is secured, and lateral nozzles projecting from said sleeve, substantially as described.

4. In a closure for disinfectant vessels, a delivery-nozzle sliding in a sleeve *h* under influence of spring *p*, a distributing-tube *e* from which project horizontal nozzles *f*, a socket *d* tapped to receive said tube and a flange *b* on

the vessel, to which said socket may be secured, substantially as described.

In testimony whereof I have hereunto set my hand in the presence of two witnesses.

HEINRICH PFLÜGER.
